UNITED STATES PATENT OFFICE

ELBERT C. LEACH AND JAY F. DOORNbos, OF OSHKOSH, WISCONSIN, ASSIGNEES TO
LEACH COMPANY, OF OSHKOSH, WISCONSIN, A CORPORATION OF WISCONSIN

PEAVEY SOCKET

Application filed February 12, 1930. Serial No. 427,744.

The present invention has to do with logging tools, and is particularly concerned with certain hereinafter described improvements in peaveys.

5 The principal object of the invention is to provide an improved peavey socket which is considerably stronger and more reliable than the sockets heretofore employed and is quite inexpensive to manufacture.

10 The invention also resides in a novel method which may be practiced in producing the socket.

While the foregoing statements are indicative in a general way of the nature of the invention, other objects and advantages will be apparent to those skilled in the art upon a full understanding of the construction, arrangement and manner of formation of the improved peavey socket.

20 One form of the invention is presented herein for the purpose of exemplification, but it will of course be appreciated that the invention is susceptible of embodiment in other structurally modified forms coming equally 25 within the contemplated scope of the appended claims.

In the accompanying drawings:

Fig. 1 is a side view of a peavey equipped with the socket of the invention;

30 Fig. 2 is a transverse section through the socket, taken on the line 2-2 of Fig. 1;

Fig. 3 is a fragmentary side view of the peavey at the location of the socket, with certain portions broken away for clearness in 35 illustration;

Fig. 4 is a perspective view of one of the filler lugs which fit between the spaced hinging ears of the socket;

Fig. 5 is a plan view of the sheet metal 40 blank from which the socket is produced;

Fig. 6 is another view of the same blank after it has been partially formed; and

Fig. 7 is an end view of the unfinished blank 45 shown in Fig. 6.

The peavey shown in the drawings is made up of a wooden handle 10, a forwardly tapering metal socket 11 into which the front end of the handle fits, a sharp pointed metal 50 pike 12 which is carried by and projects for-

wardly from the front end of the socket, and a large curved metal hook 13 which is hinged to one side of the socket at 14.

The present invention resides, not in any new combination of the above mentioned parts, because all of such parts are common to the ordinary peavey, but rather in a distinctive and much needed improvement in the construction of the socket per se, which improvement also involves a novel method of 55 production.

The socket 11 is formed up from a thin sheet metal blank 15 which is cut substantially in the shape shown in Fig. 5, with the opposite side edges 16 converging slightly, 60 and with rounded extensions 17 left on the side edges 16 adjacent the wide end 18 of the blank. The blank 15, after being cut to shape, is stamped into substantially the form shown in Figs. 6 and 7, in which form the curved 65 edges of the extensions 17 are cupped up, and the side portions of the blank, from the edges 16 inwardly for about one fourth of the width, are curved up on approximately the radius which the corresponding portions of the 70 socket are to have upon completion. The extensions 17, which subsequently constitute spaced hinging ears between which the rear 75 end of the hook is positioned, are pierced, either during the cutting or the shaping of 80 the blank, to provide bolt apertures 19, one of which is preferably squared to interfit with a squared portion 20 of the shank of a hing- 85 ing bolt 21.

After these operations have been performed, two lugs 22 of heavier sheet metal are inserted in and spot-welded to the inside faces of the cupped ears 17. The lugs are of such shape and thickness as to substantially fill the outer portions of the cavities in the ears, and are pierced to provide apertures 23 in register with the apertures 19. The lugs are provided with short out-turned flanges 24 which abut at 25 in the finished 90 product and maintain the lugs in spaced relation to each other. After the lugs have been attached to the blank in the manner described, the blank is further curved into circular form, the side edges 16 are welded 95 100

together at 26, and the pike 12 is placed in position.

The pike 12 is provided at its rear end with a short abrupt-ended frusto-conical portion 27 which has substantially the same taper and size as the front end of the inside of the socket. The pike is inserted into the socket through the rear end thereof and is moved forwardly therein until the portion 27 of the pike comes to rest in a wedged fit within the front end of the socket, after which the front end of the socket is welded at 28 to the adjacent surfaces of the pike, producing a strong and permanent connection therebetween.

The front forwardly tapering end of the handle 10 is then wedged tightly into the socket, where it is preferably held against withdrawal by a cross pin (not shown) of any suitable description, the apertured end of the hook 13 is inserted in the opening provided between the lugs 22 by the abutment of the spring flanges 23, and the hinging bolt 20 is then passed through the aligned aperture in the socket and hook and drawn up tight. The inwardly cupped portions of the edges of the ears 17 are cut away during the formation of the blank throughout the arc of swing of the hook 13 in order to accommodate the hook and at the same time permit the front and rear edges of the ears to come together.

We claim:

1. An improved peavey socket, consisting of a forwardly tapering sheet metal shell having a longitudinally extending edge joint and a pair of spaced laterally extending ears cupped toward each other at opposite sides of the joint for the reception therebetween of a hook.

2. An improved peavey socket, consisting of a forwardly tapering sheet metal shell having a longitudinally extending edge joint and a pair of spaced laterally extending ears at opposite sides of the joint for the reception therebetween of a hook, a pair of spaced reinforcing lugs positioned between the ears, a hook pivotally mounted between the lugs, and a forwardly projecting pike secured to the front end of the shell.

3. An improved peavey socket, consisting of a forwardly tapering frusto-conical sheet metal shell, and a forwardly projecting pike having a forwardly tapering frusto-conical portion fitted tightly within and secured to the front end of the shell.

4. An improved peavey socket, consisting of a forwardly tapering frusto-conical sheet metal shell having a longitudinally extending edge joint and a pair of spaced laterally extending ears at opposite sides of the joint for the reception therebetween of a hook, and a forwardly projecting pike having a forwardly tapering frusto-conical portion fitted

tightly within and welded to the front end of the shell.

5. An improved peavey socket, consisting of a forwardly tapering sheet metal shell having a longitudinally extending edge joint and a pair of spaced laterally extending ears at opposite sides of the joint, a pair of spaced reinforcing lugs secured to the inner faces of the ears for the reception therebetween of a hook, and a hinge pin extending through aligned apertures in the ears, lugs and hook. 75

6. An improved peavey socket, consisting of a forwardly tapering sheet metal shell having a pair of spaced laterally extending ears at one side thereof, a pair of spaced reinforcing lugs secured against the inner faces of the ears for the reception therebetween of one end of a hook, and a hinge pin extending through aligned apertures in the ears, lugs and hook. 80

7. An improved peavey socket, consisting of a forwardly tapering sheet metal shell having a longitudinally extending butt-welded joint and a pair of laterally extending ears at opposite sides of the joint in spaced relation to the rear end of the latter for the reception 90 therebetween of a hook.

8. An improved peavey socket, consisting of a forwardly tapering frusto-conical sheet metal shell, and a forwardly projecting pike having a forwardly tapering frusto-conical 95 portion fitted tightly within and exteriorly welded to the front end of the shell.

In witness whereof we have hereunto subscribed our names.

ELBERT C. LEACH.
JAY F. DOORNBOS.
